CLAIM

The ornamental design for a valve for engines, as shown and described.

DESCRIPTION

The patent or application file contains at least one drawing executed in color. Copies of this patent or patent application publication with color drawing(s) will be provided by the Office upon request and payment of the necessary fee.

1. Valve for engines

1.1 : bottom view;

1.2 : perspective view.

1.3 : perspective view.

1.4 : top view.

In reproduction 1.1 the dotted lines and elements encompassed by the dotted lines do not form part of the claimed design.
